UNITED STATES PATENT OFFICE.

SAMUEL D. WHEELER, OF CHICAGO, ILLINOIS.

AIR-SHIP.

No. 922,549

Specification of Letters Patent. Patented May 25, 1909.

Application filed July 25, 1908. Serial No. 445,369.

To all whom it may concern:

Be it known that I, SAMUEL D. WHEELER, a citizen of the United States, residing at Chicago, county of Cook, and State of Illinois, have invented certain new and useful improvements in Air-Ships, of which the following is a specification.

My invention relates to improvements in balloons or airships, and more particularly to means for steering the same.

The object of my invention is to render the rudder of an airship more efficient and reliable, and a further object is to provide a simple and efficient propelling means. Other objects will appear hereinafter.

With these objects in view my invention consists in a plurality of sails suitably arranged in a frame and suspended from a series of gas-bags.

20 My invention further consists in a rudder and means for generating a current of air and directing the same against the sides of the rudder in order to render it more efficient and positive in action.

25 My invention further consists in various details of construction and arrangements of parts all as will be fully described herein-after and particularly pointed out in the claims.

30 In the drawings, Figure 1, is a side elevation of the device, the body being partly broken away, and Fig. 2 is a rear elevation of the tubular air directing member.

My invention will be more readily understood by reference to the accompanying drawing forming a part of this specification, and in which—

1. indicates ordinary gas-bags which are preferably spherical in form. The sails 2 adapted to propel the ship are arranged as shown in the frame 3 which is suspended from the gas-bags. The body or basket 13 adapted to convey persons or goods is con-

nected with the frame 3 and is shown broken away in the drawing in order to expose a 45 motor 7 and a direct-connected fan 6. A rudder 5 is pivoted at the points 11 and 12 and is provided with an operating tiller 10. A tubular member 4 is interposed and adapted to direct air from the fan 6 to the rudder 50 5. The end 8 of the tubular member 4, adjacent to the fan 6, is circular and slightly larger than the circle described by the fan 6 in its revolution. The end 9, adjacent to the rudder 5, of the member 4 is flattened as 55 shown, in order that a thin sheet of air may be directed to each side of the rudder 5. The efficiency of the rudder 5 is thus increased.

Having described my invention what I claim as new, and desire to secure by Letters 60 Patent, is:

1. In an air ship a propeller and a rudder arranged behind the same, in combination with a fixed tubular member arranged between said propeller and said rudder with its axis in alinement therewith, said tubular member being flattened adjacent to the rudder, substantially as described.

2. In an air ship, a plurality of gas-bags adapted to support a frame depending therefrom, a series of sails in said frame, a basket or body for the conveyance of persons or goods connected with said frame, a rudder suitably arranged, a motor and a direct-connected fan, and a fixed tube having a circular 70 portion and a flattened or elliptical portion integral therewith and adapted to guide air from said fan to the sides of said rudder, substantially as described.

In testimony whereof I have signed my 80 name to this specification in the presence of two subscribing witnesses.

SAMUEL D. WHEELER.
